UNITED STATES PATENT OFFICE.

WILLIAM H. FOX, OF MINNEAPOLIS, MINNESOTA, ASSIGNOR OF ONE-HALF TO
BERNARD W. JAPS, OF MINNEAPOLIS, MINNESOTA.

WHEEL.

Application filed January 2, 1923. Serial No. 610,158.

My present invention relates to improvements in wheels, and more particularly to wheels having demountable rims, and has for its object to improve the same in the several particulars hereinafter noted.

To the above end, the invention consists of the novel devices and combinations of devices hereinafter described and defined in the claims.

10 In the accompanying drawings, which illustrate the invention, like characters indicate like parts throughout the several views.

Referring to the drawings:

15 Fig. 1 is an outside elevation of a disc wheel having the invention embodied therein;

Fig. 2 is a fragmentary perspective view of the parts shown in Fig. 1, on an enlarged

20 scale;

Fig. 3 is a fragmentary detail view principally in section taken on the line 3—3 of Fig. 2;

25 Figs. 4 and 5 are fragmentary perspective views of the disc wheel and demountable rim, the latter being separated from the former and tilted to show the under side thereof; and

30 Fig. 6 is a fragmentary perspective view showing a slight modification of the demountable flange.

Fig. 7 is a sectional view showing the valve stem seat.

The numeral 7 indicates a disc wheel, the 35 peripheral edge portion of which is bent laterally inward to afford a felly 8 to which is rigidly secured, by rivets or otherwise, a felly band 9. Broadly, the felly 8 and felly band 9 form an annular member which may

40 be a part of either a disc or artillery wheel. The inner edge portion of the felly band 9 is bent radially outward, and the outer edge portion thereof is bent slightly radially inward to afford oblique retaining or stop surfaces 10 and 11, respectively, and arranged to be engaged by reversely formed oblique surfaces 12 and 13, respectively, on a demountable rim 14. Said rim, between its surfaces 12 and 13, is circumferentially chan-

45 neled at 15 to remove surplus stock and to cause said rim to be supported on the felly band 9 only at its surfaces 10 and 11. Preferably, the felly band 9, between its surfaces 10 and 11, is slightly inclined inward so the

50 demountable rim 14 will move freely there-

over during its axial movement onto and off from the felly band.

It will be noted, as best shown in Fig. 2, that the surface 10 is much steeper than the surface 11 so that the surfaces 10 and 12 do not engage until the demountable rim 14 is substantially fully on the felly band 9, thereby making it extremely easy to apply the demountable rim 14 to the felly band 9 or remove the same therefrom. The felly band 9, outward of its stop surface 11, is bent to form a channel 16 that is substantially semi-circular in cross section and provided to receive and hold a transversely divided lock ring 17 for a purpose that will presently appear.

70 The demountable rim 14 is provided with an integral inner tire-retaining flange 18 and a demountable outer transversely divided tire-retaining flange 19. Formed with the demountable flange 19 is a rib 20 which is substantially semi-circular in cross section, and is mounted in a correspondingly circumferential channel 21 in the rim 14 with freedom to permit a limited axial movement of the demountable flange 19 toward and from the fixed flange 18. It is important to note that the rib 20 extends inward of the demountable flange 19 for a purpose that will presently appear.

75 Mounted on the demountable rim 14 is a pneumatic tire comprising a casing 22 and an inner tube 23 equipped with an angle valve stem 24 having opposing collars or shoulders 25 and 26, between which the inner tube is clamped to form a tight joint. This valve stem 24 projects radially inward and then laterally outward parallel to the axis of the tire, and has at its outer end a screw cap 27.

80 To permit the pneumatic tire to be applied to or removed from a demountable rim 14 by an axial movement in respect to the felly band 9 and to permit said tire and rim to be applied to the felly band 9 or removed therefrom by a like movement, the demountable rim 14 and felly band 9 and felly 8 are provided with coincident seats 28 and 29, respectively, in the form of transverse channels, the outer ends of which are open. The seat 28 is formed by pressing the demountable rim 14 radially inward, and the seat 29 is formed by forming a notch 30 in the felly band 9 and pressing the felly 8 radially inward. The seat 28 ex-

105

100

105

110

tends into the seat 29 with freedom for sliding movement transversely with the wheel. The outer edge portion of the felly band 9 is transversely notched to afford a gap 31, and which gap extends through the channel 16 and to the open outer ends of the seats 28 and 29 to receive the outer end of the valve stem 24 and its cap 27.

Both the lock ring 17 and demountable flange 19 have sufficient spring tension to tightly contract in the channels 16 and 21, respectively, and to remove the same therefrom it is only necessary to spring their ends apart to circumferentially expand said lock ring and flange. To positively circumferentially contract the lock ring 17 in the channel 16, there is provided a coupling sleeve or nut 32 having right and left-hand screw-threaded engagement with the projecting studs 33 on the ends of said lock ring.

It will be noted by reference to Figs. 2 and 3 that the demountable flange 19 extends outward of the respective edge of the demountable rim 14, and that the channels 16 and 21 are wider than the lock ring 17 and rib 20, respectively, and that said lock ring 17 directly engages the demountable flange 19 and is out of engagement with the respective edge of the demountable rim 14.

The lock ring 17 is provided with an outer circumferentially extended shoulder 34 which rests on the outer edge of the channel 16 with a knife-edge engagement.

The inner surface of the lock ring 17 has engagement with the demountable flange 19 radially outward from its shoulder 34 and is out of engagement with the bottom of the channel 16 so that, under the contraction of the lock ring 17, the same will move radially inward and thereby press the demountable flange 19 inward against the tire casing 22. The tire casing 22 rests on the rib 20 and thereby holds the same in its channel 21 against circumferential expansion. A seat 35 is formed in the demountable rim 14 at the inner end of the seat 28 to receive the collar 26 and thereby position the valve stem 24 and hold the same in its seat 28. The cap 27 engages the outer edge of the demountable rim 14 and, together with the lock ring 17, completely closes the open outer ends of the seats 28 and 29.

In mounting the tire on the rim 14 the demountable flange 19 is first removed and said tire placed on the rim 14 by a true axial movement which carries its angle valve stem 24 into its seat 28, and at the completion of the movement of the tire onto the rim 14, the valve stem shoulder 26 enters its seat 35 and is thereby positioned to hold said valve stem in the seat 28. The demountable flange 19 is next circumferentially expanded by drawing its ends apart to permit the same to be placed in the chan-

nel 21. After the tire is inflated, the same securely holds the demountable flange 19 on the rim 14 by its overlapping engagement with the rib 20 which holds the same in its channel 21, thus locking the several parts assembled which permit the tire to be carried as a spare.

The rim 14 and tire mounted thereon are then placed on the felly band 9 by a true axial movement which carries the seat 28 into the seat 29. The lock ring 17 is then circumferentially expanded by drawing its ends apart to permit the same to be placed in the channel 16. The ends of the lock ring 17 are then connected by the nut 32 and said lock ring contracted to afford common means for holding the rim 14 on the felly band 9 and the demountable flange 19 on said rim.

As previously stated, the interlocking seats 28 and 29 prevent circumferential movement of the rim 14 on the felly band 9, and to further prevent such movement there is formed on the surface 12 of said rim a rounded lug 36 arranged to enter a seat 37 in the surface 10 of the felly band 9. While only one lug 36 and the seat 37 therefor is shown, it is of course understood that a plurality of said lugs and seats may be provided in circumferentially spaced arrangement.

Referring now to Fig. 6, the construction is the same as that shown in the other figures with the exception that the demountable flange 19' is provided with an outer rib 38 which extends between the outer edge of the demountable rim 14', and the lock ring 17', and is clamped against the rim 14' by said lock ring. The other parts shown in Fig. 6 are indicated by prime numbers which correspond to like parts in the other figures.

What I claim is:

1. The combination with an annular member, of a demountable rim on the annular member and having a demountable flange, said demountable rim extending between the annular member and demountable flange and a single lock ring having separable interlocking engagement with the annular member and arranged to independently hold the demountable rim on the annular member and the demountable flange on the demountable rim.

2. The combination with an annular member having a circumferential channel, of a demountable rim on the annular member and having a circumferential channel, a circumferentially expansible demountable flange mounted in said channel, and a single lock ring mounted in the channel in said annular member and arranged to hold the demountable rim on the annular member and the demountable flange against axial removal from the demountable rim.

3. The combination with an annular mem-

- ber having a circumferential channel, of a demountable rim on the annular member and having a circumferential channel, a circumferentially expansible demountable flange 5 mounted in said channel, and a single lock ring mounted in the channel in said annular member and arranged to hold the demountable rim on the annular member and the demountable flange against axial removal from the demountable rim, said demountable flange being arranged to be held against circumferential expansion by an inflated tire on said rim.
4. The combination with an annular member having a circumferential channel, of a demountable rim on the annular member and having a circumferential channel and a circumferentially expansible demountable flange, said flange having a rib extending 15 into the channel in the demountable rim, and a single lock ring mounted in the channel in the annular member and arranged to hold the demountable rim on the annular member and the demountable flange against axial 20 removal from the demountable rim, said rib being loose in the channel in the demountable rim to permit a limited axial movement of the demountable flange on the demountable rim, whereby the pressure of an inflated tire on the demountable rim tends to 25 move the demountable flange against the lock ring and into its outermost position on the demountable rim.
5. The combination with an annular member having a circumferential channel, of a demountable rim on the annular member and having a demountable flange, and a circumferentially adjustable lock ring mounted in said channel for slight axial adjustment and having a shoulder resting on the annular member outward of its channel and supporting the lock ring for slight radial movement in respect to the annular member, said lock ring being arranged to radially overlap the demountable rim and the demountable flange 35 for direct engagement with both thereof to hold the demountable rim on the annular member and the demountable flange on the demountable rim.
6. The combination with an annular member, of a demountable rim on the annular member and having a demountable flange, and common locking means mounted on the annular member for slight axial adjustment and radially overlapping the demountable 40 rim and the demountable flange for direct engagement therewith to hold the demountable rim on the annular member and the demountable flange on the demountable rim.

In testimony whereof I affix my signature.

WILLIAM H. FOX.
